(57) **CLAIM**

The ornamental design for a folder with spring clips, as shown and described.

DESCRIPTION

FIG. 1 is a perspective view of the folder with spring clips showing our new design;

FIG. 2 is a front view thereof;

FIG. 3 is a back view thereof;

FIG. 4 is a right view thereof;

FIG. 5 is a left side view thereof;

FIG. 6 is top view thereof;

FIG. 7 is a bottom view thereof;

FIG. 8 is a perspective of an alternative embodiment of the folder;

FIG. 9 is a front view thereof;

FIG. 10 is a back view thereof;

FIG. 11 is a right view thereof;

FIG. 12 is a left side view thereof;

FIG. 13 is top view thereof; and,

FIG. 14 is a bottom view thereof.

The portions shown in phantom lines are not part of the claimed invention, but are included to show environment.
